UNITED STATES PATENT OFFICE.

THOMAS R. WRIGHT AND THOMAS B. HILL, OF PHILADELPHIA, PA.

TRIMMING ATTACHMENT FOR SEWING-MACHINES.

SPECIFICATION forming part of Letters Patent No. 257,124, dated April 25, 1882.

Application filed July 8, 1881. (No model.)

To all whom it may concern:

Be it known that we, THOMAS R. WRIGHT and THOMAS B. HILL, of Philadelphia, county of Philadelphia, State of Pennsylvania, have 5 invented a new and useful Improvement in Trimming Attachments for Sewing-Machines, of which the following is a specification.

The object of our invention is a simple and effective sewing-machine which, while being 10 operated, will trim the edges of the fabrics being sewed; and this object we attain in a manner too well described hereinafter to need preliminary description.

Our invention is shown in the accompanying 15 drawings, in which Figure 1 is a front view, partly in section, of sufficient of a sewing-machine to illustrate our improvement. Fig. 2 is a sectional end view of the same. Fig. 3 is an enlarged sectional view of that part of the 20 machine to which our invention relates, and Figs. 4 and 5 are detached enlarged sectional views.

A is the frame of the machine; B, the driving-shaft, C the feed mechanism, D the thread-hook, B the bed-plate, F the arm, G the needle-bar, and H the presser-foot, of the sewing-machine.

The driving-shaft B has a bearing in the frame A beneath the bed-plate E. Secured to 30 the shaft, or forming part of the same, is an eccentric, a, for operating the feed mechanism C. Adjacent to the said eccentric is the hook D, a stud, b, of which enters into and is secured within the eccentric. Between the eccentric a and hook D, upon the stud b, is the 35 thread-guide c. The thread-guide c we make in the shape of a short arm or cutter, c', which by the revolution of the driving-shaft to operate the feed mechanism and needle-arm is 40 caused to rotate and project at intervals through a slot made in the base-plate for the passage of the same. The end of the arm or cutter c', or that part which projects up above the bed-plate in its revolution, we form into a 45 sharp cutting-edge. A short distance from the end of the cutter-arm c', beneath the bed-plate, the said arm is bent, (see Fig. 3,) so as to bring it close to the needle.

It will be evident that the length of the bent 50 portion will be according to the desired width of the projecting ends of the seam.

The thread-guide c or cutter c' is secured to the thread-hook in the present instance by means of a screw, d. (See Fig. 4.)

In the presser-foot H we make a groove, e, 55 for the passage of the cutter-arm, (see Figs. 2 and 3,) which groove allows of the free passage of the cutter-arm, but serves as a shield for the same to prevent any accident by the cutter-arm to the operator's fingers. 60

In Fig. 5 is shown another mode of securing the cutter-arm c' to the driving-shaft B. In said figure, D is the thread-hook, C the ordinary thread-guide, and a the eccentric. The cutter c' on the stud b is secured by means 65 of the screw d to the eccentric a.

It will be evident that by securing the cutter c' to either the thread-hook or eccentric the rotation of the cutter with the driving-shaft is secured. The cutter turns freely without contact in the slot in the bed-plate, and also in the groove in the presser-foot H. By the revolution of the shaft, and consequently 70 the cutter c', the cutting-edge of the cutter is caused to project above and move along the 75 surface of the bed-plate, trimming the seam of the fabric being sewed.

By securing the cutter c' to the driving-shaft beneath the bed-plate the bed-plate is unobstructed, allowing of the free movement of the 80 material being operated on upon the bed-plate, and liability of damage to the operator's hands is avoided.

What we claim as our invention is—

1. The combination, with the main driving-shaft B, located beneath the bed-plate of the machine, of the cutter c', secured to said shaft and adapted to project upward through a slot in said bed-plate into the grooved presser-foot, substantially as described. 85 90

2. The combination, with the driving-shaft B and cutter c', of the presser-foot H, provided with the groove e, for the purpose specified.

In testimony whereof we have signed our names to this specification in the presence of 95 two subscribing witnesses.

T. R. WRIGHT.
THOS. B. HILL.
